AUTOMATIC LOCK SLIDER

Osborne Firing, Woodbury, Conn., assignor to
Scovill Manufacturing Company, Waterbury,
Conn., a corporation of Connecticut

Application February 16, 1951, Serial No. 211,395

6 Claims. (Cl. 24—205.14)

1

This invention relates to slide fasteners or zippers and particularly to automatic lock sliders for such fasteners.

This invention is an improvement on the slider shown in my copending application Ser. No. 139,332, filed January 19, 1950, the improvement having to do especially with the spring locking member.

One object of this invention is to provide an improved locking device for preventing accidental movement of the slider along the fastener stringers which will be reliable in service and which will be relatively cheaper to manufacture.

Another object is to provide a lock slider of the same general type disclosed in my prior application wherein the spring locking member is protected by a strong stationary cap member, in which the locking member has the requisite strength without objectionable overall height of the cap.

Another object is to provide improved or easier action of the spring locking member.

In the accompanying drawing I have shown for purposes of illustration two embodiments which my invention may assume in practice.

In the drawing:

Fig. 1 is a plan view of a part of a slide fastener showing the improved locking slider thereon partly in section.

Fig. 2 is a longitudinal cross-sectional view of one form of the slider as it appears in locked position on the fastener elements.

Fig. 3 is a view similar to Fig. 2 but showing the slider in unlocked position.

Fig. 4 is a perspective view of the spring lock- 30 ing element, per se.

Fig. 5 is a sectional view of a slider similar to Fig. 2 showing a modified form of spring lock- 35 ing element.

Fig. 6 is a horizontal sectional view taken along line 6—6 of Fig. 5, and

Fig. 7 is a perspective view of the modified form of spring locking element.

Referring now to the drawing in which like numerals refer to like parts throughout the several views, the numeral 10 designates generally a slider adapted to operate along slide fastener stringers of any well known type comprising fabric tapes 11 having closely spaced fastener elements 12 attached to their adjacent beaded edges.

The slider 10 comprises front and back wings or plates 13 and 14 respectively, which are integrally connected together by a wedge-shaped hollow neck 15. The side edges of the plates 13

2

and 14 are formed with the usual inwardly directed flanges 16 which with the neck 15 form a Y-shaped channel for guiding the fastener elements in opening or closing the fastener.

5 The automatic locking device includes a movable spring locking member 18 encased in a stationary cap housing 19 bearing against the upper surface of the front wing 13. The cap housing 19 comprises an elongated cupped shell, one of the 10 end walls 20 having a hooked lug portion 21 adapted to engage in a recess 22 provided in the under side of the front wing. The upper end wall 23 is extended to form a long tongue 24 fitting into the end recess 25 provided in the connecting neck 15. 15 The cap housing 19 is permanently anchored in place by wedging the tongue 24 tightly between the side walls of the recess 25 as more fully explained in the above referred to application.

The spring locking member 18, as shown in 20 Figs. 2 to 5, consists of an elongated imperforate body portion 26, one end of which is bent through a connecting arc 27 to provide a fulcrum or bearing point at 28. Depending from this bend is an elongated narrow tongue 29 which extends down 25 into the neck groove 25 of the slider neck 15. As noted in Figs. 1 and 6 the end groove 25 has parallel side walls 30 for most of its depth, which walls connect into converging walls 31 that in turn connect into a flat base wall 32 located transversely to the axis of the slider. As 30 noted in Figs. 2 and 3 the lower end of the tongue 29 is dimensioned to fit and slide against the flat base wall 32 of the neck groove 25. The narrow tongue 29 constitutes in effect the spring 35 which is free to bend in the recess 25. To provide for easy action the spring tongue preferably extends over substantially the full depth of the slider.

By providing the spring portion as an extension beyond the fulcrum point 28 I am thus able 40 to obtain maximum strength in the rigid body portion 26. This portion occupies substantially the full width of the hollow space in the cap 19 all the way back to the fulcrum point 28 so that 45 it is able to withstand the buckling stresses caused by a tearing force on the fastener when locked, all without the necessity of dependent side walls on the body member which would objectionably increase the overall height of the cap 19.

At the locking end of the member 18 there is 50 a rounded or inclined portion 33 which joins the flat end portion 34 by a bend which is reenforced by an integral rib 35. A locking prong 36 projects from the end section 34 through an opening

37 in the slider 10 to engage between the fastener elements. The locking spring 36 is preferably turned over from the side of the body member and is wider near the portion which connects to the body member so as to provide maximum strength. A pull tab 40 used to operate the slider in opening or closing the fastener has a pair of bifurcated arms 41 which straddle the cap 19 and are integrally connected by a through and through pinte 42 which extends through cutouts or openings 43 in the side walls of the cap 19 and under the locking member 18. The locking prong 36 is relieved on one side at 44 so that it can more readily enter between the fastener members or as in the case of the second embodiment it acts as a cam to allow the locking member to ratchet over the fastener elements when the fastener is being closed. The cam portion 33 is relatively long so as to provide a gentle slope against which the pull tab pinte 42 engages thus allowing easier disengagement of the locking prong from the fastener elements when the spring is under stress. The body portion of the spring 18 just rearwardly of this camming portion 33 is bent quite abruptly downwardly to provide a second camming portion 45 which continues to the curved bearing portion 46 normally resting against the upper slider wing 13 and thence upwardly to the curved end portion 27.

The slider is shown in locked position in Fig. 2 with the locking prong 36 engaged between a pair of fastener elements or scoops 12. Now when the pull tab 40 is moved in a direction to open the fastener, the pinte 42 will engage against the inclined or cam section 33 and lift the locking prong upwardly so as to free the slider. This condition is indicated in Fig. 3. During this lifting action the locking member swings about the fulcrum point 28 and the spring tongue 29 will flex to some such position as indicated in Fig. 3. Now when the pull tab is released the locking member will spring into locked position so as to lock the slider in place wherever desired along the fastener stringers.

Now when the slider is being moved into the other direction the pinte 42 will engage the inclined portion 45 and hold the locking prong away from the fastener elements. In this case there is naturally no greater force required to lift the locking member as in the case where it may be binding against a fastener member. In this form of the invention the middle portion of the locking member rests normally against the slider and accordingly it is not necessary to provide any additional means for holding the locking member in place.

The embodiment shown in Figs. 5, 6 and 7 is generally the same in construction and operation as the first embodiment and similar reference numerals indicate like parts. It is intended for use where the ratcheting for the locking pin is not objectionable and accordingly the middle bent portion is omitted and the member continues straight from the front cam section 33 all the way to the curved fulcruming end 27. By way of further modification the additional locking prong 50 may extend from the body member and in somewhat staggered relation so as to engage between a pair of fastener elements on the opposite stringer.

In this embodiment it is probably desirable to hold the spring member in place by some such means as the indentations 51 in the side walls of the cap.

As a result of my invention it will be evident

to those skilled in the art that I obtain the well recognized advantages of a protected or enclosed locking member while at the same time keeping the overall thickness of the slider to a minimum. At the same time I provide a spring locking slider which will have relatively easy action in unlocking. It is also economical to manufacture since it can be formed from a small sheet metal blank; the locking member is preferably made from stainless steel which will not rust and which will have the maximum strength for the minimum space.

I claim:

1. A slider for slide fasteners comprising front and back plates connected at one end by a neck, an exterior groove extending lengthwise of said neck, a hollow cap member attached to the slider and extending lengthwise of the front plate and overlapping said groove, a locking member confined within said housing having a locking prong at one end adapted to extend through an opening in the front plate to lock the slider against movement along the fastener, said locking member having a rigid body portion extending from the prong end to engage the end wall and also the upper wall of the cap adjacent that end of the cap opposite from the locking prong to provide a fulcrum, a spring tongue depending from the fulcrum into said groove and being free to flex within said groove, the end of said spring tongue engaging a wall of the groove and normally set to hold said locking prong in engagement with the fastener members, a pull tab pivoted to said cap, and a cam portion on said locking member engageable by said pull tab to lift the locking prong out of the slider channel against the tension of said spring tongue.

2. A slider as defined in claim 1 wherein the body portion of the locking member is substantially as wide as the hollow space in the cap and wherein the tongue is relatively much narrower throughout its length whereby the body is rigid and the tongue is springy.

3. A slider as defined in claim 1 wherein the locking member is a thin metal strip of uniform rectangular cross section between the locking prong and the fulcrum point.

4. A slider as defined in claim 1 wherein said neck groove extends across the entire depth of the slider and wherein said spring tongue also extends for substantially the entire length of said groove.

5. A slider as defined in claim 1 wherein said cam portion of the locking member is joined to the portion carrying the prong with a bend and wherein an integral reinforcing web extends across said bend.

6. A slider as defined in claim 1 wherein the attachment of the upper end of the cap member is accomplished by a tongue wedged tightly between opposite walls of said groove and wherein there is a substantial space between said tongue and back wall of the recess to permit freedom of movement of said spring tongue on the locking member.

OSBORNE FIRING.
